UNITED STATES PATENT OFFICE.

CHARLES E. BARTRAM, OF FREDONIA, NEW YORK.

KNOCKDOWN FRUIT-BARREL.

SPECIFICATION forming part of Letters Patent No. 281,230, dated July 17, 1883.

Application filed April 2, 1883. (No model.)

To all whom it may concern:

Be it known that I, CHARLES E. BARTRAM, a citizen of the United States of America, residing at Fredonia, in the county of Chautauqua and State of New York, have invented certain new and useful Improvements in Knockdown Return Fruit-Barrels, of which the following is a specification, reference being had therein to the accompanying drawings.

10 This invention relates to barrels to be returned to the shipper after each shipment of fruit, &c., and it is constructed so as to leave a space between the staves and at both ends for ventilation, and for folding it up flat when 15 not in use; and the invention consists in its particular construction, as fully hereinafter claimed.

In the drawings, Figure 1 is a perspective of my barrel complete and in shape for use; 20 Fig. 2, the barrel collapsed and doubled flat; Fig. 3, detail in perspective of the fastening to the heads, bottom view; and Fig. 4, an enlarged detail of the hoops' ends held together by the links.

25 *a a a* designate the staves, made flat, rectangular, and without bulge, having the usual croze near the ends for the reception of the two head-pieces *b b b*, which, when in, leave an open space, *c*, between the two for the insertion of the fastening and expanding device A, one at each end of the barrel. This is 30 made of a flat piece of wood, *d*, with a downwardly-projecting piece, *e*, fastened to the under side thereof, one side rounded or beveled off, and the other side, *e'*, hollowed out, as 35 shown in Fig. 3. This is set into the space *c* in the barrel-head by first catching the part *e'* under the head and pressing down on the flat part *d*. The rounded side allows the whole to

slip into place, besides expanding the barrel 40 into proper shape or roundness, as shown in Fig. 1. This fastening device A is kept in place by a button, *h*, or any suitable device.

fff are the metal bands made into hoops by uniting their ends to metal links or loops 45 *g g*, two to each hoop and set exactly opposite to each other, just halving the barrel, so that when collapsed the barrel folds together or doubles on itself, as shown in Fig. 2, lying down perfectly flat and held at the ends by 50 the links *g*, which unite the hoops and act as hinges to open and close the barrel. The hoops or metal strips are each nailed to the staves, one at each end of the barrel, as shown, and one in the middle.

55 This is the entire construction, which is very simple, strong, durable, and cheap. It is "knocked down" into a small flat space for return, as shown in Fig. 2. The advantages of this need not be enumerated, as they are 60 too well known.

I claim—

The knockdown return shipping-barrel, consisting of the staves *a a a*, the attached metal bands or hoops *fff*, having the uniting-links *g g* opposite each other, and the head-pieces *b b*, and the head-fastening devices A *d e' e'*, and means for holding the head-fastening devices against the head-pieces, all constructed, combined, and arranged substantially as specified.

65 In testimony whereof I affix my signature, in presence of two witnesses, this 17th day of March, 1883.

CHARLES E. BARTRAM.
